ATTORNEY

UNITED STATES PATENT OFFICE.

ABRAHAM ALEXANDER, OF TROY, NEW YORK.

LUGGAGE-TRUCK.

1,043,038.

Specification of Letters Patent.

Patented Oct. 29, 1912.

Application filed October 2, 1911. Serial No. 652,277.

To all whom it may concern:

Be it known that I, ABRAHAM ALEXANDER, a citizen of the United States, residing at Troy, county of Rensselaer, and State of New York, have invented certain new and useful Improvements in Luggage-Trucks, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a view in side elevation of a traveling-case strapped upon my improved luggage-truck, showing the folding foot extended to support the truck and its load in upright position, and showing one of the extensible legs of the truck in vertical section. Fig. 2 is a top plan view 25 of the truck with one of the straps removed, and the other strap partly broken away. Fig. 3 is a cross-section of the same taken on the broken line 3—3 in Fig. 1, viewed in the direction of the arrow.

The principal object of the invention is to provide for luggage ordinarily carried by hand, a simple truck whereby articles of different sizes and of considerable weight can be conveniently rolled along a floor or 35 sidewalk, guided and controlled by the operator.

Referring to the drawings wherein the invention is shown in preferred form, 1, represents the platform of my improved truck, 40 which is adapted to support a packing-case, 2, or the like, strapped upon said platform by means of a plurality of straps, 3, each of which is threaded through a pair of slots, 4, in the platform-plate, said straps being 45 adapted in the usual manner to embrace and hold articles of different sizes, while the top stretch of the strap affords a grasp for the hand of the operator in guiding and controlling the movements of the truck.

Fixed to the underside of the platform-plate, 1, is a substantially U-shaped plate, 5, the arms, 6, of which extend divergently downward and are provided with a plurality of bolt-apertures 7. An extension-leg 55 8, similarly provided with a plurality of bolt-apertures, 9, is mounted upon each of

the arms, 6, said extension-leg being secured to the arm in a selected one of the various positions in which said leg can be applied to the arm, with certain of the bolt-apertures, 9, registering with certain of the bolt-apertures, 7, to receive the bolts, 10, which are secured in position by means of thumb-nuts 11. By bringing into alinement different bolt-apertures in the arm, 6, and leg, 8, said leg can be more or less extended to support the truck-platform, 1, at different heights to accommodate it to articles of different sizes, or to accommodate it for convenient use by persons of different heights. Upon the outer end of each leg, 8, is a foot, 13, having a roller, 14, mounted thereupon upon a horizontal axis. The foot, 13, is mounted upon the leg, 8, to rotate upon a substantially vertical axis thus forming a caster.

In using the device the luggage article is strapped upon the truck-platform, and the legs, 8, are more or less extended in accordance with the size of the package and the height of the operator, and the truck and its load are propelled along the floor or sidewalk by the hand of the operator which grasps the upper stretch of one of the straps 3. I have also shown the truck provided with a folding-foot, 15, whereby the truck and its load can be supported in upright position without the aid of the operator. Said foot is preferably made of wire in the form shown in Fig. 3, with its outer end of sufficient width to afford a stable support, 90 the branches of the wire being bent or offset inward to bring them within the lateral dimensions of the legs, 8, whereby the offset-portions, 16, of the wire are adapted to bear upon the leg, 8, to assist in supporting the folding-foot, 15, in its extended position.

The branches of the wire are formed with spring-coils, 17, which embrace a pivot-pin, 18, mounted in ears or lugs, 19, formed on the leg, 8, the ends, 20, of the wire being extended to bear upon said leg to render said springs, 17, effective. The springs, 17, act to extend the foot.

To fold the foot it is swung by hand from the position shown by solid lines back upon the leg, 8, as indicated by dotted lines in Fig. 3, in which folded position it is held by means of a button, 21, pivoted at, 22, upon the leg, 8, the ends of the button when extended crosswise of the leg being adapted to overlap the offset-portion, 16, of the foot, thereby securing the foot in folded position.

When the folding-foot is extended, its outer end is adapted to engage the floor or sidewalk at a sufficient distance laterally from the roller to prevent the loaded truck 5 from tipping over.

What I claim as new and desire to secure by Letters Patent is—

1. In a luggage-truck, and in combination, a platform; straps whereby articles of different sizes can be secured upon said platform; extensible legs for supporting said platform; and casters upon the outer ends of the respective extensible legs.

2. In a luggage-truck, and in combination, a platform; means for securing articles of different sizes upon said platform; a pair of arms extending downward from said platform provided with a plurality of bolt-apertures; extension-leg members provided with 20 bolt-apertures; bolt-connections between each of the extension-leg members, and one of said arms adapted to lock the parts together, with the leg more or less extended; and a caster upon the outer end of each extension-leg member.

3. In a luggage-truck, and in combination, a platform; straps whereby articles of different sizes can be secured upon said plat-

form; extensible legs for supporting said platform; casters upon the outer ends of the respective extensible legs; and a folding-foot mounted upon the extensible member of one of said legs adapted when said foot is extended to support the truck and its load in upright position.

4. In a luggage-truck, and in combination, an extensible leg for the truck; a roller upon the outer end of an extensible member of said leg; a folding-foot formed of wire having offset portions adapted to bear upon the extensible member when the foot is extended, having its ends adapted to bear upon said extensible member, and having spring-coils; a pivot-pin mounted upon said extensible member and embraced by said spring-coils; and locking-mechanism mounted upon said extensible member adapted to engage and hold said foot in folded position.

In testimony whereof, I have hereunto set my hand this 27th day of September, 1911.

ABRAHAM ALEXANDER.
